DECATIZING FABRICS

Paul Rose, Clifton, N. J.

Application October 21, 1936, Serial No. 106,919

8 Claims. (Cl. 38—15)

This invention relates to improvements in the art of decating or decatizing fabrics and more particularly to a novel arrangement for decatizing textile fabrics to obtain a desired finish thereupon.

It is the object of the present invention to accomplish the decatizing of fabrics more efficiently, quickly, and satisfactorily than has been possible heretofore in the art. The invention is applicable to all types of textile fabrics such as cottons, woolens, silks, rayons, and the like, or to fabrics formed by mixtures of such fibers.

It is an object of the invention to decatize fabrics while the web of fabric is passing from a take-off reel to a winding reel without the necessity of winding the web of fabric upon a perforated decatizing cylinder with the attendant tedious operation of winding the fabric with a backing adjacent thereto preparatory to the conventional decatizing steaming and drying treatments.

It is a further object of the invention to finish a textile material by decatizing in such a manner that every length of the material is assured exactly the same treatment as the next adjacent length in order to obtain a uniformly finished product. This is not the case with the fabrics finished in the manner previously known in the art, in which case the material adjacent the decatizing cylinder is subjected to a different degree of treatment from the material more remote from the cylindrical core. This objection is not eliminated entirely by a reverse winding of the fabric with its backing upon another cylinder for a repeated treating operation, which incidentally is time-consuming and expensive.

It is a further object of the invention to provide a machine capable of decatizing all types of fabrics so that the final set thereof may be accurately controlled. By the critical adjustment of the tension under which the fabric is fed through the machine and the pressure between the two pressing surfaces through which the fabric passes in the course of its steaming, the desired set may be imparted to the fabric, and a crepy effect, smooth, dull, or glossy finish may be obtained.

It is a further object of the invention to provide a machine in which the hot steaming treatment may be accomplished without danger of burning the material on the one hand, or damaging it by water spots occasioned by the condensation of steam on the other hand.

It is a further object of the invention to provide one or more drying and conditioning units

with the decatizing unit in order to complement the latter in obtaining the desired finish for the material.

Other objects and purposes will appear from the more detailed description of the invention following hereinafter in conjunction with the accompanying drawings wherein:

Figure 1 is a plan of the arrangement in accordance with the invention, showing in general the serial location of the parts shown in greater detail in the following figures.

Figure 2 is a longitudinal sectional view of the first unit of the decatizing machine performing the steaming and pressing operations.

Figure 3 is a plan view of the machine shown in Figure 2.

Figure 4 is a plan view of the drying unit adjacent the decatizing unit shown on a smaller scale in Figure 1.

Figure 5 is a longitudinal sectional view of Figure 4.

Figure 6 is a top plan view of the final drying and conditioning unit shown on the right end of Figure 1.

Figure 7 is the longitudinal sectional view of Figure 6.

Figure 8 is a top plan view of the upper surface of the lower steaming chamber in Figure 2, and

Figure 9 is a bottom view of the upper suction chamber in Figure 2.

In the drawings, the assembly in accordance with the present invention is illustrated as being composed of three frame units 1, 71, and 91 positioned in tandem. The web of fabric F in the course of its processing passes from the winding-off reel 4 at the left end of Figure 1 to the winding-up reel at the right of Figure 1.

The roll of fabric to be processed on reel 4 is mounted in suitable bearings upon the bracket 2 attached to the machine frame 1 (Figure 2). Slightly in advance of the roll 4 is disposed a pair of posts 7 upon which are adjustably mounted a frame 8 revolvably supporting expander rolls 9 and 10 across the width of the machine. The web of fabric F is passed between these rolls as shown in Figure 2 for the purpose of removing wrinkles in the fabric.

The fabric F is then passed through a pair of tension rolls 12 mounted in suitable bearings which may be supported by the bracket 2. These rolls may be driven by a motor 60 through the intermediary of a speed reducing device 61 and a variable speed controlling device 62 in order to obtain a fine degree of control for the speed of these rolls and thereby to regulate the tension

of the fabric in the course of its travel through the processing stages. With a controlled tension at this point it is possible to decatize effectively crepes, woolens, knitted and similar fabrics without any stretch or shrinkage. Any speed reducing device or variable speed control arrangement may be availed of in the practical application of the present invention and these units are illustrated merely schematically for the purpose of explaining the present invention.

The web of fabric is then passed through the decatizing unit which consists principally of two endless porous bands or blankets of textile, metallic or composite material pressed towards each other with a predetermined force depending upon the material being treated and the final finish which is desired, and through which bands is passed the steaming medium to exercise the desired control upon the texture of the fabric in conjunction with the pressure imposed thereupon. The upper blanket 19 is disposed upon the two blanket rolls 15 and 16 which may be made of steel and which may have a peripheral surface which is plain, knurled, or fluted. Either one or both of these rolls may be power driven, and as shown in Figure 1, the roll 15 is driven by motor 63 through the intermediary of a gear reducer 64 and the roll 16 is driven from the shaft 15s carrying the roll 15 by means of the sprocket chain 65. Likewise the lower blanket 20 which may be of the same or different material from that composing blanket 19 is disposed on the blanket rolls 17 and 18 and is actuated thereby. As shown in Figure 2, the drive for the latter rolls is derived from the shaft 15s by gear 15g which is mounted thereon meshing with the gear 11g mounted on the shaft carrying roll 17. A sprocket chain 65' may extend between sprockets mounted on the driving shafts for the rolls 17 and 18 to actuate both of these rolls.

A plurality of guide rolls 21 are mounted rotatively in the sides of the machine for the purpose of guiding the upper blanket in its course of travel, and in order to regulate the tension of this blanket and for the purpose of taking up slack and variations in length occasioned by temperature changes and the like, the following regulating arrangement is provided at the top of the machine for the upper blanket. Upon a bearing bracket 23 fixed upon the machine frame is disposed guide rolls 24 and 25 which, in conjunction with a guide roll 26 mounted on a movable support 27, guide the blanket in a reverse loop. The position of the slidable support 27 is controlled by a threaded shaft 28 cooperating with a threaded bore in the support 27, the rectilinear movement of which is enforced by the guide shaft 27a. Rotation is imparted to shaft 28 by means of a regulating hand wheel H and bevel gears 29 and 30 to control the length of the reverse loop which is formed by the blanket and consequently the tension under which the endless blanket operates.

A similar adjusting arrangement for the lower blanket is provided at the lower portion of the machine in which the parts 23', 24', 25', 26', 27', 27a', 28', 29', and 30' operate in the manner described above in relation to the corresponding parts.

Above the lower run of the upper blanket 19 is disposed a suction chamber 32 having the bottom surface 32s thereof provided with a plurality of apertures 52 (Figure 9) which cooperate with the porous upper blanket. This compartment 32 is designed to be maintained at a partial vac-

uum by the connection thereto of a suitable evacuating apparatus such as a steam ejector, vacuum pump, or the like.

A steam chamber 42 is disposed below the lower blanket 20 and is composed of two superposed compartments. Steam is admitted to the lower chamber 42 and serves as an insulating jacket for the upper chamber 43 which comes in contact with the porous blanket 20. Hot steam is circulated through the lower chamber by an admission conduit 44 and an exhaust conduit which is not shown. The top surface 43s of the chamber 43 is perforated with apertures 51 (Figure 8) in order to present the live steam introduced into the chamber 43 to the porous blanket 20 which is sucked therethrough and the intervening fabric as well as upper blanket 19 by the low pressure prevailing in chamber 32. The backing of the chamber 43 with a hot steam chamber 42 assures the steaming of the fabric by the penetration of the steam therethrough without the formation of any water spots thereon and the consequent damage to the fabric. By suitably controlling the temperature of the steam introduced into the chamber 43 and that introduced into the chamber 42 a fine control of the heat treatment adaptable to any particular goods is obtained.

An important feature of the present invention consists in the adjustability of the force exerted by pressing surfaces between which the fabric is treated. Such a feature is completely lacking in the practices of the prior art in the decatizing of fabrics. One form of realization of this function is illustrated in Figure 2 wherein the chamber 42 is provided at one end with journal pins 45 which are connected with a system of levers 46, 47, and 48 which upon rocking cause a lifting of the chamber and are likewise controlled by a system of rocking levers 46', 47', and 48'. A lever 49 connects the two lever systems described above and causes them to act in unison and under control of a lever 50 which may be weighted as at 51 to govern the force with which the chamber 42 is pressed against the undersurface of the blanket 20. A shifting of the weight 51 or a variation thereof causes a corresponding difference in pressure between the bands 19 and 20. In the illustrated embodiment of the invention, the top surface 43s is shown as roof-shaped so that the pressure exerted upon the fabric as it passes between the bands is characterized by a gradually increasing gradient and then a gradually decreasing gradient.

Following the decatizing as described above, the fabric F is dried and conditioned to permit the fabric to assume the set which is desired. This operation may be performed with a single dryer or more than one. Thus as shown in Figure 1, two dryers may be connected in series to execute the drying operation. In the first of these dryers, mounted in frame 71, the fabric is allowed to dry naturally with or without the aid of supplemental air currents to cause the fabric to assume a natural set. In the dryer mounted in frame 91, the fabric is subjected to a forced air drying and conditioning, which may be modified by controlling the temperature and the humidity of the circulating air. These dryers may be used to the exclusion of each other or other forms of dryers may be substituted in lieu of the types disclosed in dependence upon the specific results sought to be obtained.

In Figures 4 and 5 are shown enlarged views of a rack dryer which is in the form of an endless conveyor formed by two side chains 81 and 75

between which are revolvably mounted rolls 74 which support the fabric in naturally dropping festoons as it is fed thereto. The drag roll 75 guides the material on to the rolls 74 as they 5 progressively come into position to receive the material and the drag roll 77 takes off the fabric from the rolls 74. The drag rolls may be interconnected by a chain 79 which may be driven by a sprocket on the shaft 78' on which the drag roll 78 is mounted. The drive for the conveyor sprocket 72 may also be derived from the same shaft 78' through the intermediary of a transmission chain 80. The main conveyor sprockets 12 are provided with peripheral notches 13 to 10 accommodate the rolls 74 in the course of travel 15 thereover.

The web of fabric passes from the dryer 71 to the guide roll 94 mounted upon the final dryer 91. In this unit the fabric is passed over a perforated endless blanket which may be of plush 20 or other fine material and which is actuated about rolls 87 and 88 and guide rolls 96. Below the perforated band is provided a suction chamber 93 in which sub-atmospheric pressure 25 is maintained by blower 92b actuated by the electric motor 92.

The final drier unit is driven by motor 85 through the intermediary of adjustable speed reducing mechanism 86 which critically controls 30 the speed of shaft 87. A chain 83 extends between the rolls 87 and 88 and from the latter extends the transmitting mechanism for controlling the actuation of the moving elements in the intermediate dryer 71. The transmission chain 35 84 extends between sprockets on shaft 87' and 95' and actuates the drag roll 95 mounted rotatively upon the bracket 100 attached to the end of the machine. Adjacent this drag roll 40 are mounted inclined bearings 102 for the take-off shell or winding reel 101 for receiving thereupon the processed goods. The drag roll 95 drives the shell by frictional contact therewith and as the latter increases in diameter with the accumulation of the fabric thereupon, the shell 45 merely works upwardly in the inclined bearings 102 until the processing of the length of fabric is completed.

A variation of the speed of the drag roll 95 50 controls the output of the machine and at any one setting thereof the yield of processed fabric is constant.

The transmission mechanism described above 55 may be altered in several respects without departing from the spirit of the invention. Such changes will suggest themselves to those skilled in the art and since the embodiment disclosed herein has been presented for purposes of illustration only, the scope of the invention is to be construed by the annexed claims.

60 What I claim is:

1. In an apparatus for continuously decatizing fabrics, two longitudinally movable superposed pervious pressing surfaces adapted to receive the fabric therebetween, a vacuum chamber adjacent one of said surfaces and a steam chamber adjacent the other one of said surfaces, said chambers being provided with openings adjacent to said pressing surfaces, means for adjusting the contact pressure between said two surfaces, and means for advancing conjointly the two pressing surfaces with the fabric therebetween to effect by the application of steam and pressure to the fabric a change in the finish thereof.

75 2. In an apparatus for continuously decatizing

fabrics, two endless porous pressing bands adapted to receive the fabric therebetween, a suction chamber adjacent one of said bands and a steam chamber adjacent the other one of said bands, said chambers having perforated surfaces in contact with said bands, means for adjusting the contact pressure between said two bands, and means for actuating the bands conjointly with the fabric therebetween to effect a decatizing treatment thereof by the application of steam 10 and pressure.

3. An apparatus for continuously decatizing fabrics, two superposed porous pressing surfaces adapted to receive the fabric therebetween, a suction chamber adjacent one of said surfaces 15 and a steam chamber adjacent the other one of said surfaces, said chambers having perforations therein in contact with said pressing surfaces, a plurality of compartments in said steam chamber including a heated compartment spaced from 20 the perforations in the steam chamber for providing a heat-insulating backing for the steam passing through the perforations, and means for advancing conjointly the two pressing surfaces with the fabric therebetween while applying 25 steam and pressure thereto.

4. An apparatus for continuously decatizing fabrics, two superposed porous pressing surfaces adapted to receive the fabric therebetween, a suction chamber adjacent one of said surfaces 30 and a steam chamber adjacent the other one of said surfaces, said chambers having perforations therein in contact with said pressing surfaces, means for varying the pressing force imposed upon the fabric by the two pressing surfaces, 35 means for pre-tensioning the fabric prior to its introduction between the pressing surfaces, and means for actuating the two pressing surfaces with the fabric therebetween with the simultaneous application of steam and pressure thereto 40 to effect a decatizing thereof.

5. In an apparatus for continuously decatizing fabrics, two endless porous pressing bands adapted to receive the fabric therebetween, a suction chamber adjacent one of said bands and a steam 45 chamber adjacent the other one of said bands, said chambers having perforated surfaces in contact with said bands, means for adjusting the contact pressure between said two bands, means for pre-tensioning the fabric prior to its 50 introduction between the pressing bands, and means for advancing the two pressing bands with the fabric therebetween while applying steam and pressure thereto.

6. An apparatus for continuously decatizing 55 fabrics, two superposed porous pressing surfaces adapted to receive the fabric therebetween, a suction chamber adjacent one of said surfaces and a steam chamber adjacent the other one of said surfaces, said chambers having perforations 60 therein in contact with said pressing surfaces, means for pre-tensioning the fabric prior to its introduction between the pressing surfaces, and means for actuating the two pressing surfaces with the fabric therebetween with the simultaneous application of steam and pressure thereto 65 to effect a decatizing thereof.

7. In an apparatus for continuously decatizing fabrics, two endless porous pressing bands adapted to receive the fabric therebetween, a suction 70 chamber adjacent one of said bands and a steam chamber adjacent the other one of said bands, said chambers having perforated surfaces in contact with said bands, means for adjusting the contact pressure between said two bands, means

- for pre-tensioning the fabric prior to its introduction between the pressing bands, means for advancing the two pressing bands with the fabric therebetween while applying steam and pressure thereto and means for drying the fabric comprising an endless chain conveyor having transversely disposed supporting rollers, and means for feeding the fabric on to said rollers in the form of festoons to permit a drying of the fabric to impart a natural set thereto.
8. In an apparatus for continuously decatizing fabrics, two endless porous pressing bands adapted to receive the fabric therebetween, a suction chamber adjacent one of said bands and a steam

chamber adjacent the other one of said bands, said chambers having perforated surfaces in contact with said bands, means for adjusting the contact pressure between said two bands, means for pre-tensioning the fabric prior to its introduction between the pressing bands, means for advancing the two pressing bands with the fabric therebetween while applying steam and pressure thereto, and means for drying the fabric comprising an endless porous blanket for supporting the fabric and a perforated suction chamber underlying the blanket to effect a forced drying of the fabric.
